DESIGN FOR A SUITCASE

Benjamin M. Hamlin, Chicago, Ill., assignor to Universal Trunk Company, Chicago, Ill., a corporation of Illinois

Application February 2, 1939, Serial No. 82,729

Term of patent 7 years

To all whom it may concern:

Be it known that I, Benjamin M. Hamlin, a citizen of the United States and resident of Chicago, in the county of Cook and State of Illinois, have invented a new, original, and ornamental Design for a Suitcase, of which the following is a specification, reference being had to the accompanying drawing, forming a part thereof,

Fig. 1 is a view in perspective of a suitcase showing my new design;

Fig. 2 is a side elevational view of the same.

I claim:

The ornamental design for a suitcase, substantially as shown.

BENJAMIN M. HAMLIN.
